NOZZLE

Franklin E. James, Almont, Pa., assignor to Mack Manufacturing Corporation, Long Island City, N. Y., a corporation of Delaware

Application June 4, 1943, Serial No. 489,629

3 Claims. (Cl. 299—138)

The present invention relates to nozzles by means of which fluids may be directed in any desired direction and embodies, more specifically, an improved form of nozzle having mechanism by means of which the flow of fluid may be changed as desired. More particularly, the invention embodies mechanism by means of which the flow of fluid through the nozzle may be treated in such fashion as to produce a great quantity of small particles, forming, in effect, an artificial fog of sufficient driving or carrying power to be directed against the desired objective.

In apparatus for fighting fires adjustable nozzles have heretofore been provided, the purpose of which has been to vary the characteristics of the water or fluid directed at the fire. In certain instances it is desirable to produce a fog which causes the fire to be blanketed and smothered, and an object of the present invention is to provide a nozzle by means of which such a fog may be produced.

A further object of the invention is to provide a mechanism having adjustable means therein, by means of which the fluid flow may be readily controlled to form a fog having the desired properties, the mechanism including means for interrupting the lamellar flow of fluid through the nozzle.

Other and further objects of the invention will be apparent as it is described in greater detail in connection with the accompanying drawing, wherein:

Figure 1 is a partial view in section taken longitudinally of a nozzle constructed in accordance with the invention;

Figure 2 is a view in section, taken on line 2—2 of Figure 1;

Figure 3 is a view similar to Figure 1 showing the position of the adjusting mechanism to produce a different character of fluid flow than that shown in Figure 1; and

Figure 4 is a view similar to Figure 1, showing a further adjusted position of the nozzle mechanism.

The form of nozzle chosen to illustrate the invention and shown in Figures 1 to 4, includes a casing 40 which is provided with an outlet aperture 41 and a pair of plugs 42 mounted upon the shafts 43. The plugs are formed with eccentric grooves 44 which combine to produce a passage that can be varied in size as well as in position with respect to the axis of the nozzle. For example, as illustrated in Figure 1, the plugs 42 are in a position to afford a maximum passage through the nozzle at the axis thereof. As shown in Figure 2, this passage may be of circular cross-section.

In Figure 3, each of the plugs has been turned through 180 degrees, and the flow of the fluid through the nozzle is diverted as indicated by

the arrows, so that two streams are formed which converge in the nozzle outlet 41 and produce a maximum interference to form a fog. The position of the plugs, as shown in Figure 4, produces a modified fluid flow with turbulence due to the pockets formed on the outlet sides of the plugs 42.

It will be understood that the nozzle may be provided with a suitable sleeve which may be threaded to permit it to be secured to a hose connection and that mechanism may be included to permit orientation of the nozzle casing 40.

From the foregoing, it will be seen that a nozzle has been provided having a capacity for maximum adjustment to produce a stream of fluid having a desired characteristic of simulating a fog, and that the stream may be varied not only to vary the character of the fog, but also of the force with which the stream is directed toward the fire.

While the invention has been shown with reference to the specific form of nozzle illustrated in the accompanying drawing, it is not to be limited save as defined in the appended claims.

I claim:

1. A nozzle comprising a casing formed with a passage for fluid therethrough and semi-cylindrical cavities therein adjacent to one end of said passage, a pair of cylindrical plugs rotatably supported in said cavities and having peripheral portions engaging the casing and each other, a groove extending around the major portion of the periphery of each plug and eccentric thereto, and means for rotating said plugs to permit fluid to flow through said grooves between the plugs or to flow through said cavities between said plugs and said casing and to vary the flow of fluid therethrough.

2. A nozzle comprising a casing formed with a passage therethrough between the inlet and outlet ends thereof, the outlet end being formed with a discharge orifice, rotatable plugs in the nozzle having their peripheral portions in engagement with the casing and with each other, a groove of varying depth extending partially around the periphery of each plug, and means to rotate the plugs to vary the character of the flow of fluid through the nozzles.

3. A nozzle comprising a casing formed with a passage therethrough between the inlet and outlet ends thereof, the outlet end being formed with a discharge orifice, rotatable plugs in the nozzle having their peripheries in engagement with said casing and with each other, a groove extending around the periphery of and eccentric to each plug, the groove bottom being tangent to the periphery of said plug at one point, and means to rotate the plugs to vary the character of the flow of fluid through the nozzle.

FRANKLIN E. JAMES.
